UNITED STATES PATENT OFFICE.

EDWARD B. ENTWISLE, OF JOHNSTOWN, PENNSYLVANIA, ASSIGNOR TO THE
JOHNSON COMPANY, OF SAME PLACE.

BOX-CHAIR FOR RAILROAD-RAILS.

SPECIFICATION forming part of Letters Patent No. 442,175, dated December 9, 1890.

Application filed May 26, 1890. Serial No. 353,197. (No model.)

To all whom it may concern:

Be it known that I, EDWARD B. ENTWISLE, of Johnstown, in the county of Cambria and State of Pennsylvania, have invented a new and useful Box-Chair for Railroad-Rails, which invention is fully set forth and illustrated in the following specification and accompanying drawings.

The object of this invention is sufficiently indicated by its title above given.

The invention will first be described in detail, and then particularly set forth in the claim.

In the accompanying drawings, Figure 1 shows the chair in end elevation having a rail, shown in cross-section, seated thereon. Fig. 2 is a side elevation of Fig. 1, looking to the right. Fig. 3 is a view in plan, and Fig. 4 a view in perspective, of the chair, the rail being omitted in both figures.

In said figures the several parts are respectively indicated by letters of reference

as follows: The letter A indicates the chair proper; a, the rail-seat; B B, the vertical sides of the chair, and b b its lower flanges or feet. The letters C C indicate two lugs, located diagonally opposite each other, stamped out of the sides B B of the chair and bent over to clamp the lower flanges of the rail, as shown in Fig. 1. The spaces left in the sides of the chair by the stamping out of the lugs C C are indicated by the letters D D.

It is obvious that the form of the upper portion of the rail used is not material, as the chair is adapted to seat many forms of rail.

Having thus fully described my said invention, I claim—

A box-chair for railroad-rails, provided with diagonally-located lugs cut out of the sides and bent over from the seat of the chair.

E. B. ENTWISLE.
